CLAIM

The ornamental design for a terrestrial telescope, sub-
stantially as shown and described.

DESCRIPTION

FIG. 1 is a perspective view of a terrestrial telescope
showing my new design;

FIG. 2 is an elevation view showing the left side
thereof;

FIG. 3 is an elevation view showing the right side
thereof;

FIG. 4 is a top plan view thereof;

FIG. 5 is a bottom plan view thereof;

FIG. 6 is a front elevation view thereof;

FIG. 7 is a rear elevation view thereof; and

FIG. 8 is a longitudinal cross-sectional view thereof.

FIG. 1

FIG. 2

FIG. 3
